Primary Examiner — Jack Reickel*Assistant Examiner* — Michael A Kervin(74) *Attorney, Agent, or Firm* — Norton Rose Fulbright US LLP(57) **CLAIM**

The ornamental design for a door lock keyboard, as shown and described.

DESCRIPTION

FIG. 1 is a front elevation view of the door lock keyboard according to our new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is an enlarged view of portion A shown in FIG. 7; and, FIG. 9 is an enlarged view of portion B shown in FIG. 7. As shown in the enlarged view of FIG. 9, the middle part of the door lock keyboard is concave.

1 Claim, 8 Drawing Sheets(56)
